UNITED STATES PATENT OFFICE.

JEPTHA D. PATTERSON, OF ABBOTTS, NEW YORK.

DEVICE FOR AERATING MILK.

SPECIFICATION forming part of Letters Patent No. 323,069, dated July 28, 1885.

Application filed April 18, 1884. (No model.)

To all whom it may concern:

Be it known that I, JEPTHA D. PATTERSON, a citizen of the United States, residing at Abbotts, in the county of Cattaraugus and State 5 of New York, have invented certain new and useful Improvements in Devices for Aerating Milk; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 My invention relates to a device for aerating milk; and it consists in the novel construction, combination, and arrangement of the several parts, as will be hereinafter described and claimed.

20 In the drawings, Figure 1 is a side view of my device, the cylinder being broken away to show the piston. Fig. 2 is a detail view of the piston. Figs. 3, 4, 5, and 6 are detail views of the piston, all of which will be 25 described.

The cylinder A is open at its upper end, and is contracted at its lower end to form a nipple, a, on which is fitted the air-discharge tube composed of sections B and C, 30 the former of which tapers to its lower end, and is made of the same external diameter as the nipple a. The section C has its lower end adapted to fit on the lower end of the section B or the nipple a. The joints between 35 the sections and the upper section and the nipple are made detachable, usually, by just slipping one on the other so the sections may be interchangeably used or used together at will. The section C, it will be noticed, is

40 shorter than B, so by using first both sections, as shown, then removing section C, and subsequently substituting section C for B, I am able to force air into three different strata of the milk. The number of sections 45 may be increased to suit the will of the maker. I have only shown two sections, as they illustrate the spirit of my invention. The tubes being of a small diameter do not practically disturb the cream which may have

risen on the milk. The air-piston D operates 50 within the cylinder A, and has the arms d extended from the lower end of its rod D. The lower ends of these arms are threaded to receive the nuts d'. The disks E F are provided with perforations slipped over the 55 arms d. Central concentric apertures, e f, are formed through these plates, the former, e, being the smaller, as shown in Fig. 3. A leather or other suitable elastic disk, G, is clamped between these plates by the nut d' 60 being turned up against the lower plate. I make the disk G of a larger diameter than the disks E F, so it will extend beyond said disks, as clearly shown, and form the packing between the same and the walls of the 65 cylinder. The flap-valve g is cut from the center of this leather disk, and is made of a diameter to fit and operate within opening f, and yet large enough to operate over the opening e, around which the valve sits when 70 closed.

The operation is simple, and will be readily seen. With the downward stroke of the piston the valve closes, and air is forced into the milk. On the upstroke of the piston the 75 valve opens, permitting air to enter the cylinder, and preventing the piston from sucking the milk up, as will be understood.

By making the peripheral packing and the valve of the piston from the same piece of 80 leather, a simple and cheap construction is provided.

My piston can be easily taken apart for the purpose of cleansing or renewing any of the parts, as will be understood.

Having described my invention, what I 85 claim, and desire to secure by Letters Patent, is—

The herein shown and described milk-cooling device, consisting of a cylinder contracted at its lower end to form a nipple and provided with interchangeable pipe-sections of varying lengths, in combination with a piston working in said cylinder, composed of a rod having arm-extensions branching from its 90 lower end, threaded on their outer extremities to receive a pair of concentrically-apertured disks between which is interposed a disk of 95

leather the periphery of which extends beyond the edges of the disks, the three being confined by nuts on the threaded ends of said arms, the opening in the upper disk being 5 smaller than the opening in the lower disk to form a seat for a flap-valve cut in the center of the leather disk, as shown, and for the purpose described.

In testimony whereof I affix my signature in presence of two witnesses.

JEPHTHA D. PATTERSON.
